CLAIM

The ornamental design for a portable information terminal, as shown and described.

DESCRIPTION

FIG. 1 is a perspective view of front, top and left side of a portable information terminal showing my new design; FIG. 2 is a perspective view of front, top and left side thereof; FIG. 3 is a perspective view of front, bottom and right side thereof;

FIG. 4 is a perspective view of rear, top and left side thereof;

FIG. 5 is a front view thereof;

FIG. 6 is a rear view thereof;

FIG. 7 is a left side view thereof;

FIG. 8 is a right side view thereof;

FIG. 9 is a top plan view thereof; and,

FIG. 10 is a bottom plan view thereof.

The broken lines shown in the figures that exist on unshaded surfaces, adjacent to shaded surfaces, represent environment that is understood to create boundaries between claimed and non-claimed areas, while the broken lines that exist within those boundaries represent environment; the broken lines form no part of the claimed design.
